DESIGN FOR A BOX OR SIMILAR CONTAINER

Duryea Bensel, New York, N. Y.

Application December 24, 1936, Serial No. 66,717

Term of patent 14 years

To all whom it may concern:

Be it known that I, Duryea Bensel, a citizen of the United States, residing at New York, in the county of New York and State of New York, and whose post office address is 11 West 42nd Street, New York, N. Y., have invented a new, original, and ornamental Design for a Box or Similar Container, of which the following is a specification, reference being had to the accompanying drawing, forming part thereof.

In the drawing,

Fig. 1 is a front view in elevation, of a box or similar container and Fig. 2 is an end view in elevation thereof, showing my new design, the rear side and end of Figs. 1 and 2 having duplicate designs thereon, respectively.

I claim:

The ornamental design for a box or similar container as shown and described.

DURYEA BENSEL.
